UNITED STATES PATENT OFFICE

2,613,805

STORAGE BOX FOR CLOTHES

Louise K. Frolich, Kansas City, Mo.

Application July 19, 1951, Serial No. 237,614

3 Claims. (Cl. 206—7)

1

This invention relates to storage boxes, and more particularly to boxes for storing clothing or the like which may be collapsed to flat position when not in use.

The principal objects of the present invention are to provide a storage box preferably made from relatively stiff cardboard or the like of one piece material having score lines to form the box when in use; to provide a support for hangers of the garments in the ends of the box; to provide means for holding the garments flat against the bottom of the box so that they will remain in extended position and thus prevent wrinkling of the garment; and to provide means for sealing the box so that it may be used for a period of time as desired.

In accomplishing these and other objects of the present invention, I have provided improved structure, the preferred form of which is illustrated in the accompanying drawings, wherein:

Fig. 1 is a perspective view of the storage box with parts broken away to better illustrate the invention.

Fig. 2 is a perspective view of the box in partially flat condition with parts broken away to better illustrate the invention.

Fig. 3 is a cross-sectional elevational view of one end of the box showing the garments placed therein.

Fig. 4 is a fragmentary elevational view of one end of the box showing the hanger support.

Fig. 5 is a fragmentary elevational view of one of the rods to hold the clothes in position.

Referring more in detail to the drawings:

I designates a storage box embodying the features of my invention made from a single sheet of material 2 such as cardboard, corrugated board or the like, and provided with ends 3 and 4, separated from the main body of the box by transverse fold lines 5 and 6. The main body of the box is provided with longitudinal fold lines 7, 8, 9 and 10. When the sheet of material is folded on said fold lines, the box comprises a bottom 11, sides 12 and 13, having extensions 14 and 15 forming a cover for the box. The ends 3 and 4 are provided with fold lines 16 and 17 forming end flaps 18 and 19 so that when the box is folded, the end flaps 18 and 19 will engage the ends of the sides 12 and 13, and may be fastened thereto by sealing tape or the like as indicated at 20 (Figs. 1 and 3).

Secured to the bottom 11 of the box near the respective ends thereof by rivets or the like 21 are hinges 22 and 23 for accommodating rods 24 and 25. Secured near the upper or outer edges of the

ends 3 and 4 are keeper members 26 and 27 for receiving a latch portion 28 of a chain 29 secured to the outer end of the rods 24 and 25 as indicated at 30 (Fig. 4). The rods provide a support for hangers 31 for the clothing as indicated at 32 (Fig. 3).

Hingedly connected to the respective sides 12 and 13 of the box as indicated at 33 (Fig. 5) are rods 34 and 35. The outer ends of the rods are provided with heads 36 forming recesses 37 spaced from the ends of the rod and the heads are adapted to engage in keepers 38 as best illustrated in Fig. 5. The rods are of a length substantially equal to the width of the box when in folded position.

My box is particularly adapted to be collapsed and stored in flat condition for use by storage companies until they are desired to be delivered to the customers.

In assembling the box for use, the sheet of material is folded on lines 8 and 9 and the ends are folded on lines 5 and 6 with the end flaps 18 and 19 extending around the sides 12 and 13 and secured thereto by tape or the like.

The rods 24 and 25 are then extended and the latching head of the chain 29 is engaged with the keepers 26 and 27 respectively. The box is then ready for storage of the garments and they may be placed therein on hangers and the hangers engaged over the rods as indicated at 39 (Fig. 3). The clothes may be secured in either end, and if they are long enough the tails or skirts of the garments may overlap each other. When the garments are in place, the rods 34 and 35 are then extended across the garments and the heads 36 engaged in the keepers 38, also as illustrated in Fig. 3.

The box is particularly adaptable for storage of blouses, shirts and the like, and will prevent wrinkling while in storage. The rods 34 and 35 will also tend to form a more rigid box. The keepers 38 are provided with spring members 40 for retaining the heads 36 therein while in use.

When the box is not in use, the hanger supports and rods are disengaged from the keepers and lie flat along the bottom and sides, respectively, of the box. When the box is filled with clothing, the flap 14 is closed over the top and the flap 15 placed thereover and sealed with sealing tape or the like, as indicated at 41 (Fig. 1). The sealing tape may extend over the entire cover member and onto the ends of the box if desired.

It will be obvious from the foregoing that I have provided an improved collapsible storage box having hanger support and means for hold-

ing the garments in place to prevent wrinkling thereof while in storage.

What I claim and desire to secure by Letters Patent is:

1. A box for storing clothing on hangers or the like comprising, a bottom, sides, ends and cover members, rods hingedly connected to said bottom near the ends thereof, keepers on the end members near the outer edges thereof, chains on the free ends of said rods having latch portions engaging said keepers to form supports for the clothing on the hangers in the respective ends of the box, rods hingedly connected to the sides of the box offset from one another, keeper members on the sides of the box opposite said rods, and heads on the end of the rods for engaging in said keepers whereby the rod engages the clothing for holding the clothing in flat condition in the box, said first named rods being foldable along said bottom and the other rods along said sides when the box is in flat condition.

2. A box for storing clothing therein on hangers or the like comprising, a sheet of relatively stiff material having spaced longitudinal fold lines and transverse fold lines whereby said sheet may be folded forming a bottom, sides, ends and cover members for said box, said end members having longitudinal fold lines forming end flaps for folding around the sides of said box, means for securing said end flaps to said side members, rods hingedly connected to said bottom near said transverse fold lines, keepers on the end members near the outer edges thereof, chains on said rods having latch portions engaging said keepers to form supports for the clothing on the hangers in the respective ends of the box, rods hingedly connected to the sides of the box offset from one another, keeper members on the sides of the box opposite said rods, heads on the free ends

of the rods for engaging in said keepers whereby the rods engage the clothing for holding the clothing in flat condition, and means for sealing the cover members.

3. A box for storing clothing therein on hangers or the like comprising, a sheet of relatively stiff material having spaced longitudinal fold lines and transverse fold lines forming end members whereby said sheet may be folded forming a bottom, sides, ends and cover members for said box, said end members having longitudinal fold lines forming end flaps for folding around the sides of said box, means for securing said end flaps to said side members, rods hingedly connected to said bottom near said transverse fold lines, keepers on the end members near the outer edges thereof, chains on the free ends of said rods having latch portions engaging said keepers to form supports for the clothing on the hangers in the respective ends of the box, rod means carried by the respective side members and engaging said clothing for holding same in flat condition in the box, said rods being foldable along said bottom and the rod means along said side members when the box is in flat condition, and means for sealing the cover members.

LOUISE K. FROLICH.
